UNITED STATES PATENT OFFICE.

EDWARD FLICEK, OF MILWAUKEE, WISCONSIN.

CURTAIN-FIXTURE.

SPECIFICATION forming part of Letters Patent No. 703,955, dated July 1, 1902.

Application filed May 23, 1901. Serial No. 61,491. (No model.)

To all whom it may concern:

Be it known that I, EDWARD FLICEK, a citizen of the United States, residing at Milwaukee, county of Milwaukee, and State of Wisconsin, have invented new and useful Improvements in Curtain-Fixtures, of which the following is a specification.

The object of my invention is to provide a device for draping or adjustably supporting the lower free ends of window or door curtains, whereby the same may be looped up and supported at a greater or less height above the floor or at a greater or less distance from the window or door frame.

15 The construction of my invention is explained by reference to the accompanying drawings, in which—

Figure 1 represents a front view of a window provided with curtains and my curtain-supporting mechanism. Fig. 2 is a detail showing one of the curtain-supporting devices removed from the window-frame. Fig. 3 represents a modified form of the supporting-bracket, which is used for the vertical adjustment only.

Like parts are identified by the same reference-letters throughout the several views.

The curtains A A are suspended from the top of the window-frame B in the ordinary manner. To the respective sides of the window-frame are attached the curtain-supporting brackets C and D by screws or nails, as indicated in Fig. 1. The brackets C and D are provided with adjustable curtain-supporting hooks E, which hooks are made of elastic material and are so constructed that the arms G G are adapted when released from pressure to spring apart and impinge upon the rods H of the brackets, whereby they are adapted to remain at any point of adjustment.

When desirous to adjust the hooks E upwardly or downwardly, it is necessary simply to press the arms G G toward each other, whereby they are free to move upwardly and downwardly. In the preferred form of supporting-hook E (shown in Fig. 2) the arms G G are bent at nearly right angles to the supporting-rod H, forming hand-bearings I I, by which they are more readily compressed when 50 in the act of adjusting them.

In the form shown upon the left in Fig. 1 the bracket C is provided at its upper end with an angular bend J in addition to the bends M M, by which as the supporting-hook E is raised it is also carried toward the 55 left and farther away from the window-casing, as may in some cases be desired, while in the form of bracket shown upon the right both its upper and lower end are secured at the same distance from the window-frame. 6c

The brackets C and D are provided at their ends with loops or eyes K for the reception of retaining-screws, while the arms G G of the supporting-hook are also provided with loops or apertures L L for the reception of said brackets. In the form shown the supporting brackets and hooks are made of wire bent into the desired shape; but it is obvious that the same may, if desired, be struck up from sheet metal without departing from the spirit of my 70 invention. It is also obvious that while I have shown my device supported from window-frames it is equally adapted to be used in connection with door-frames or any other place where it is desired to drape or support 75 curtains.

Having thus described my invention, what I claim as new, and desire to secure by Letters Patent, is—

1. In a device for draping the lower ends of 80 curtains, the combination with the side of a supporting-frame; of a supporting-bracket rod; a hook formed with forked shank-arms of elastic material and provided with bracket-receiving apertures therein; said arms being 85 adapted to spread sufficiently when in normal position to cause the bracket-rod to bind in said apertures.

2. The combination of a curtain-supporting frame; an angular bracket connected with 90 said frame; a slideable hook supported on said bracket; having means for automatically locking said hook at any desired point of adjustment upon said bracket, said hook being adapted, by the angular shape of its supporting-bracket, to be adjusted nearer to, or farther away from, said curtain-supporting frame, substantially as specified. 95

3. In a device for draping the lower ends of 100 curtains, the combination with the side of a

supporting-frame; of a supporting-bracket rod; a curtain-holding device formed of a piece of resilient wire doubled upon itself and bent in the form of a hook, with the free ends 5 extending divergently to form a forked shank, and looped to form end apertures for the insertion of the bracket-rod; said shank ends being normally separated sufficiently to cause

the looped ends of the wire to bind on the bracket-rod.

In testimony whereof I affix my signature in the presence of two witnesses.

EDWARD FLICEK.
